TOY PISTOL

Herman Milstein, Los Angeles, Calif.

Application May 6, 1946, Serial No. 667,622

1 Claim. (Cl. 124—27)

1

This invention relates to projectile propelling devices and relates more particularly to an embodiment constructed as a toy pistol.

The primary object of the present invention is to provide a toy pistol which is characterized by its simplicity of construction and operation, its general safety in use, its sturdiness, and its economy of manufacture.

Another object of the invention is to provide a toy pistol in which the barrel serves as an inner guide for the projectile and in which a trigger-released spring of novel form and arrangement propels a projectile along the barrel and therebeyond.

Another object of the invention is to provide a toy pistol in which the projectiles are strung or passed over the barrel, and in which a trigger-released spring, formed with a loop engaged over the barrel, engages behind the projectiles to propel them along and off the end thereof.

per them along and off the end thereof.

My invention also has for its objects to provide such means that are positive in operation, convenient in use, and of general superiority and serviceability.

The invention also comprises novel details of construction and novel combinations and arrangements of parts, which will more fully appear in the course of the following description. However, the drawing merely shows and the description merely describes two embodiments of the present invention, which are given by way of illustration or example only.

In the drawing:

Fig. 1 is a top plan view of a toy pistol embodying the present invention.

Fig. 2 is a side elevational view thereof.

Fig. 3 is an enlarged front view.

Fig. 4 is a top plan view, the barrel being broken away of a modification.

Fig. 5 is a side elevation view thereof.

The embodiments of the invention which are illustrated, each comprise, generally, a stock 10, a barrel 11 fitted thereon, a projectile propelling spring 12, and trigger means 13 for retaining the spring cocked and for releasing the same to propel a projectile P along and off the end of the barrel 11.

In the form of the invention shown in Figs. 1, 2 and 3, the stock 10 is formed of a flat piece of wood, plastic or similar material which is shaped to provide a handle grip 14 and a forward extension 15. A groove 16 is provided in the extension for housing the trigger means 13.

The barrel 11 comprises a length of rod 17 firmly pressed into the end of the extension 15 at 18.

2

The barrel, in this instance, is shown as of round cross-section, it being obvious that it can be of other sectional form and even helically twisted for effecting rotation of a projectile mounted thereon.

The spring 12 is formed in the manner of a clasp or safety pin, being made of a length of spring wire with a pivoted leg 19, a barrel engaging leg 20, and a helically coiled integral connecting portion 21. The leg 19 is formed with an eye 22 mounted in a cross pin 23 in the stock extension 15. The leg 20 is formed with an end loop 24 which engages over the rod 17 freely. Adjacent said loop, the leg 20 is provided with a 15 transverse offset 25 generally aligned with the center line of the pistol.

The trigger means, in this instance, comprises a single member mounted to pivot on a transverse pin 26 and in the slot or groove 16 of the stock extension 15. The member is formed with a hook 27 adapted to engage the mentioned offset 25 of the spring 12 and with a finger piece 28. The hook 27 and the finger piece 28 are on opposite ends of the trigger so that a rearward and upward pull on the finger piece will result in a generally downward movement of the hook 27. A spring 29 is provided to give resiliency to the action of the trigger and to normally hold the hook 27 in position to latch onto the offset 25.

30 The hook 27 is designed and located to engage the offset 25 of the spring 12 and to hold the legs thereof pressed toward each other. The hook 27 is readily engaged with said offset by merely re-
35 tractively pressing the leg 20 toward the leg 19 and permitting the offset 25 to wedge itself past the angled edge 30 of the hook 27 and thereby depressing the trigger until the spring 29 be-
comes effective to engage the hook 27 with the offset 25.

40 By stringing a projectile **P** over the barrel so that it rests against the spring loop **24** and re-
tracting the trigger by pulling back on the finger
piece **28**, the spring is released so that said loop
45 **24** slides along the barrel and thereby propels
the projectile from the barrel. As shown, by the
dot-dash lines of Fig. 2, the spring **12** expands
so that a considerable angle, one in excess of
90°, is formed between the legs **19** and **20**. It
will also be noted that the loop **24** retains en-
50 gagement with the barrel in readiness for again
cocking the spring.

In the modification of Figs. 4 and 5, the handle grip 31 is formed, as before described, of flat stock. In this instance, the extension 32 is formed as a cylindrical member into which said handle

grip is mortised, as shown. Except for the trigger means 12, the other elements of the pistol are similar to those above described. The trigger means, instead of moving downwardly to release the spring 12, moves laterally to effect such release. The offset 25, therefore, not being needed, is omitted.

The trigger means of the modification includes a finger piece 33 pivoted on a transverse pin 34^a in the extension 32 and formed with an upstanding end 34. The trigger means also includes a latch 35 pivoted on a vertical pin 36 in said extension. Said latch is formed as a bell crank lever having an apertured arm 37 engaged with the end 34 and an arm having a hook 38, similar to the hook 21, on its end. It will be evident that by pulling on the finger piece 33 to cause its end 34 to move forward in a vertical plane, the latch 35 will move in a horizontal plane to cause lateral disengagement of the hook 38 from the spring leg 20 and thereby release the stored energy of the spring 12.

A suitable slot 39 is provided in the extension 32 to house the finger piece 33 and a transverse slot 40 is similarly provided for the latch 35.

While I have illustrated and described what I now regard as the preferred embodiments of my invention, the construction is, of course, subject to modifications without departing from the spirit and scope of my invention. I, therefore, do not wish to restrict myself to the particular forms of construction disclosed, but desire to avail myself of all modifications that may fall within the scope of the appended claim.

I claim:

In a toy pistol having a stock formed with a

handle grip and having a rod extending therefrom, there being a spring-urged trigger pivotally mounted in said stock, said trigger terminating in a hook that extends from the stock below said rod, the improvement that comprises 5 means for propelling a projectile strung on said rod, said means comprising a length of spring wire pivotally connected to the stock below the pivot of the trigger and extending downward from said stock, a helical spring coil integrally formed on the lower end of said length of wire, a second and longer length of wire integrally extending upwardly from said coil and terminating in an open loop engaged over the rod, and an integrally formed and laterally directed portion 10 provided in an intermediate part of said second length of wire and adapted for releasable engagement with the mentioned hook on the trigger to hold the projectile-propelling means releasably tensioned.
